UNITED STATES PATENT OFFICE.

CHARLES J. WILLIAMS, OF PROSSER, WASHINGTON.

CHAIN-PUMP.

No. 873,280.

Specification of Letters Patent.

Patented Dec. 10, 1907.

Application filed June 19, 1906. Serial No. 322,490.

To all whom it may concern:

Be it known that I, CHARLES J. WILLIAMS, of Prosser, Benton county, and State of Washington, have invented certain new and useful improvements in a chain-pump for the elevation of water for irrigation and to lift water to relieve and clear mines, the pump being for mining irrigating purposes; and I do declare the following to be a full and clear description of the invention, such as will enable others skilled in the art to which it appertains to make and use the same.

The invention relates to the means and devices for pumping water; specially in connection with irrigation and mining, where water under pressure is not required.

The object of my improvements is to provide simple, inexpensive and efficient means for the purposes herein mentioned.

In the accompanying drawing, Figure 1 is a side elevation of my improved pump; Fig. 2 is a top plan view thereof; Fig. 3 a cross section taken on line 3 of Fig. 2 and viewed in the direction of the arrow; Fig. 4 a horizontal section taken on line 4 of Fig. 1 and viewed in the direction of the arrow; Fig. 5 a side elevation, partly in section, of the chain carrying wheels; Fig. 6 is a longitudinal section on lines 6 of Fig. 1 and viewed in the direction of the arrow.

Like letters of reference denote similar parts in the several figures.

P is a pump stock provided at its lower end with a cut-away portion P' and at its lower end with a spout H. The stock P is closed at its upper end by a flanged cap G bolted to the supporting frame work M and serving to hold the stock in true vertical line. At the bottom of the stock P I provide a circular flange P² encircling the stock and the flange has a pair of upwardly extending angular brackets J provided at their ends with journal bearings J' in which are journaled the shaft S of the lower pair of chain carrying wheels F.

Q are metallic bands which are formed into two hoops with a central connecting web as best shown in Fig. 4, one of the hoops of these bands encircle the stock P intermediate its ends and in the other hoops of these bands are mounted the strips I which form a guide for the buckets as will hereinafter appear.

M designates a rectangular frame to the under side of which the flange G is attached by means of the bolts G'. L is a second frame similar to the frame M and adapted to

rest upon the same. K—K are a series of bolts passing through the frame L and having their lower ends resting above plates O mortised into the upper surface of the frame M. N are tapped nuts mortised into the under side of the frame L through which the bolts pass. By this construction it will be seen that the frame L can be adjusted toward and away from the frame M for the purpose of tightening the tension on the bucket carrying chains in a manner to be hereinafter described.

R' designate a pair of bearings mounted on the upper side of the frame L in which is mounted the shaft R having at one end the gear A with which meshes the gear B on the shaft T mounted in bearings T' which are also supported on top of the frame L. C is a driving pulley also carried by the shaft T. From this it will be seen that when power is applied to the pulley C in any suitable way the shaft R will be driven through the gears A and B.

F are a pair of chain carrying wheels mounted on the shaft R in line with the pair of chain carrying wheels F' mounted upon the shaft S. Running over these wheels are the pair of chains E upon which are mounted the buckets D which preferably are of the construction shown in Figs. 1 and 5. Preferably and as shown, the chains E are in sections and are connected to the buckets by means of the U-shaped bolt V passing through the bottom of the bucket and having a plate U passing over the free ends of the bolt V and secured in place by means of suitable nuts on the ends of the bolt. One section of the chain being attached to the loop of the bolt V and the section of the chain on the other side of the bucket being attached to the plate U at the ends of the bolt. Preferably and as shown, the wheels F and F' are provided with a peripheral groove F² in which the chains run and are also provided with one or more sector shaped openings F³ in their periphery into which the buckets extend, as clearly shown in Figs. 1 and 5. In the form of construction shown the buckets are so placed apart upon the chain and the wheels F and F' are of such a size that but one slot is needed on the periphery of each wheel. If the buckets were set closer together it would, however, as will be readily understood, be necessary to provide more slots in the wheels.

From the above description of the construction of my invention it will be apparent

that when power is supplied to the pulley C the wheels F will be driven and will carry the pump carrying chain down the guide-way formed by the strip I in to the cut-away portion of the stock P and thence up the stock.

By providing the two frames L and M with their adjusting means it is possible to take up any slack in the chains by merely setting up the screws K. This adjustment being located at the top of the pump renders the same readily accessible irrespective of the location of the lower end of the pump.

As will be noted by my construction of pump, the structure is entirely suspended and supported from its upper end and no side bracing of the pump stock is required, and the connections between such pump stock and the chain guides are such that each serves to preserve the true vertical alinement of the other, and the bucket carrying chain is caused to travel in a true line throughout its entire path.

While I have described what I believe to be the preferred form of my invention, I desire to have it understood that many changes may be made in the form, construction and arrangements of parts without departing from the spirit of my invention.

What I claim as new and desire to secure by Letters Patent is:—

1. In a chain pump, the combination with

a stock, of a guide formed of a plurality of separated strips, hoops surrounding the strips to support the strips in position, and means extending from the hoops and engaging the stock to hold the guide parallel to the stock.

2. In a chain pump, the combination with a frame, a stock supported from the frame, a second frame mounted over the first frame, means for adjusting said second frame toward and away from the first frame, chain operating mechanism including a chain pulley upon the upper frame, a second chain pulley secured to the lower end of the stock and a pump chain extending over said pair of pulleys.

3. In a chain pump, the combination with a frame, a stock supported from the frame, a second frame mounted over the first frame, means for adjusting said second frame toward and away from the first frame, chain operating mechanism including a chain pulley upon the upper frame, a second chain pulley secured to the lower end of the stock and a pump chain extending over said pair of pulleys and having buckets mounted thereon.

CHARLES J. WILLIAMS.
